6 Claims. (Cl. 254—93)

ABSTRACT OF THE DISCLOSURE

The hydraulic ram carries a conically-faced valve at its bottom end which contacts a stop ring carried by the tank nut when the ram has reached the upper limit of permissible travel to unseat and connect the pressure face of the ram with the reservoir. The top end of the ram cylinder extends inside of the tank nut but is not secured to it so that it is free-floating or unstressed.

Our invention relates to hydraulic jacks and, in particular, to a valve arrangement for connecting the pressure cylinder with the tank when the ram has reached the limit of its stroke.

It is an object of our invention to provide a valve arrangement that eliminates the "weep hole" normally used in hydraulic jacks.

It is another object to provide a valve arrangement that permits the use of rubber packings instead of the more expensive leather packings.

The above and other objects of the invention are accomplished by means of a construction in which a valve member is movably attached to and carried by the ram and is normally held by oil pressure on a valve seat formed on the bottom end of the ram. When the ram reaches the limit of its travel, the valve contacts a stop that separates it from its valve seat on the ram to permit oil in the ram cylinder to flow into the tank.

The invention is illustrated in the accompanying drawings in which:

FIGURE 1 is a plan view of a jack embodying the invention;

FIGURE 2 is an elevation taken from the right of FIGURE 1;

FIGURE 3 is an enlarged cross section taken primarily on a midplane of FIGURE 1 but with a portion thereof offset to reveal the pump cylinder and piston; and

FIGURE 4 is a partial cross section taken substantially at right angles to the section of FIGURE 3 and modified to include various oil passages.

The jack 1 has a base 3 with a boss 5 on which the bottom end 7 of the tank cylinder 9 is seated and welded in a fluid tight joint 11. The top end 13 of the cylinder 9 is closed by a shouldered tank nut 15 which is welded to it in a fluid tight joint 17. A ram cylinder 19 is coaxial with tank cylinder 9 and is fixed on the base 5 inside a recess 21. The top end 23 of the ram cylinder 19 extends within but is spaced from the wall of an enlarged aperture 25 in the tank nut 15 so that there is clearance 27 connecting the space 29 above the top end of the cylinder 19 with the tank or reservoir chamber 31 surrounding the cylinder.

The ram 35 moves up and down inside the ram cylinder 19. It has an aperture 37 extending downwardly from its top end 39 and in it is fixedly positioned a sleeve 41 that is internally threaded to engage the external threads on extension screw 43 that has a cap or head 45 to engage the load to be lifted. Obviously, the overall length of the ram assembly can be varied by screwing the screw 43 up or down in aperture 37.

The bottom end 47 of the ram 35 has a frusto-conical shape with a horizontal face 49 and an annular tapering

2

surface 51 that acts as a valve seat for the frusto-conical top end of a valve member 53 which has a horizontal face 55 spaced from ram face 49 and an annular tapering valve surface 57 mating with valve seat 51. The valve 53 is carried by the ram 35 through the agency of a screw 59 that extends through a hole 61 in the valve and threads into a hole 63 in the bottom end of the ram. The valve 53 has an enlarged aperture 65 aligned with hole 61 and seated against the shoulder so formed is a coil spring 67 that acts against the head of the screw 59 to resiliently urge the valve 53 onto its valve seat 51.

The outer periphery of the valve member 53 has an annular recess 69 in which are positioned an O-ring seal 71 and a back-up washer 73.

It will be understood that to use the jack by raising the ram 35 fluid pressure must be applied by suitable means against the bottom face 75 of the valve member 53. The seal 71 prevents such pressure from by-passing the valve 53 and accordingly the ram 35 and attached parts will rise inside the cylinder 19. During this period oil pressure holds the valve on the ram seat 51. When the ram reaches the permitted limit of its travel, the annular shoulder 77 on the top of the valve 53 engages the bottom face of a stop and ram bearing ring 79 in the tank nut 15. It is separated by an O-ring seal 81 from an upper ram bearing ring 83 that presses against a retainer ring 85 that fits in a groove inside the tank nut 15. This resistance to upward movement of the valve member 51 unseats it from valve seat 53 since the ram 35 is not so obstructed. Oil under pressure can then flow through valve aperture 63, hole 61, the space between flat faces 55 and 49, past the valve surfaces 57 and 51, and into the space 29 and clearance 27 at the top end of the ram cylinder whereby it is connected with the reservoir 31. As soon as the pressure drops sufficiently the load on the ram and the spring 67 will cause the valve 53 to seat again but continued pumping of oil will again unseat it in the manner just described. This seat-unseat action may repeat as long as oil under pressure is furnished to the bottom of the ram assembly.

The structure for furnishing oil under pressure to operate the jack forms no part of the invention and may be conventional. Such structure is illustrated in the drawings wherein the hand pump handle 101 operates through a link 103 to reciprocate pump piston 105 in bore 107. The bore 107 is connected through passages 109 and 111 to an enlarged passage 113 that connects through passage 115 to the bottom of the ram cylinder 19. Oil from the reservoir 31 passes through filter 117 to enter passages 119 and 121 which connect with the passages mentioned above whereby oil reaches the pump chamber 107. Suitable spring seated ball check valves 123 and 125 prevent mis-flow during pumping and suction strokes. A hand operated release valve 127 is positioned in suitable apertures (not shown) so that upon release turning thereof passage 113 is connected through another passage (not shown) to the bottom of the reservoir 31.

It will now be realized that the invention provides a simple but effective means to automatically limit the upward travel of the ram and that this permits the use of highly effective pressure compressed O-ring seals.

Modifications may be made in the structure illustrated without departing from the spirit and scope of the invention.

We claim:

1. A hydraulic jack comprising a base, a tank cylinder mounted on the base, a ram cylinder mounted on the base inside the tank cylinder, the space between said cylinders comprising a reservoir for oil, a ram movable up and down inside the ram cylinder, a valve seatable on the bottom of the ram and carried thereby and having a pressure face exposed to oil pressure in the ram cylinder,

said valve being movable relative to the ram and urged by pressure to seat on the ram, means for pumping oil from the reservoir to the ram cylinder under pressure, stop means mounted at the top of the tank cylinder and engageable with the valve to unseat it from the ram, and fluid passage means open when said valve is unseated to connect the pressure face of said valve with said reservoir, the bottom of said ram and the top of said valve having engageable annular conical faces acting to prevent flow when engaged through said fluid passage means.

2. A hydraulic jack comprising a base, a tank cylinder mounted on the base, a ram cylinder mounted on the base inside the tank cylinder, the space between said cylinders comprising a reservoir for oil, a ram movable up and down inside the ram cylinder, a valve seatable on the bottom of the ram and carried thereby and having a pressure face exposed to oil pressure in the ram cylinder, said valve being movable relative to the ram and urged by pressure to seat on the ram, means for pumping oil from the reservoir to the ram cylinder under pressure, stop means mounted at the top of the tank cylinder and engageable with the valve to unseat it from the ram, and fluid passage means open when said valve is unseated to connect the pressure face of said valve with said reservoir, said valve having a central aperture through it and including a screw extending through said aperture and mounting the valve on the ram and a spring mounted on the screw and urging the valve onto its seat on the bottom of the ram.

3. A jack as set forth in claim 2 wherein the bottom of said ram and the top of said valve have engageable annular conical faces acting to prevent flow when engaged through said fluid passage means.

4. A jack as set forth in claim 3 including a tank nut mounted at the top of the tank cylinder, a retainer ring carried by the tank nut, a pair of ram bearing rings carried by said tank nut and reacting against said retainer ring, an O-ring seal between said bearing rings and engaging the ram to prevent leakage of oil from the jack, at least one of said bearing rings providing said stop means, said valve having an external annular groove and an O-ring seal seated in said groove and engaging the inside wall of the ram cylinder to prevent oil leakage between the valve and ram cylinder.

5. A hydraulic jack comprising a base, a tank cylinder mounted on the base, a ram cylinder mounted on the base inside the tank cylinder, the space between said cylinders comprising a reservoir for oil, a ram movable up and down inside the ram cylinder, a valve seatable on

the bottom of the ram and carried thereby and having a pressure face exposed to oil pressure in the ram cylinder, said valve being movable relative to the ram and urged by pressure to seat on the ram, means for pumping oil from the reservoir to the ram cylinder under pressure, stop means mounted at the top of the tank cylinder and engageable with the valve to unseat it from the ram, and fluid passage means open when said valve is unseated to connect the pressure face of said valve with said reservoir, a tank nut mounted at the top of the tank cylinder, a retainer ring carried by the tank nut, a pair of ram bearing rings carried by said tank nut and reacting against said retainer ring, an O-ring seal between said bearing rings and engaging the ram to prevent leakage of oil from the jack, at least one of said bearing rings providing said stop means, said valve having an external annular groove and an O-ring seal seated in said groove and engaging the inside wall of the ram cylinder to prevent oil leakage between the valve and ram cylinder.

6. A hydraulic jack comprising a base, a tank cylinder mounted on and rigidly secured to the base, a ram cylinder mounted on the base inside the tank cylinder, the space between said cylinders comprising a reservoir for oil, a ram movable up and down inside the ram cylinder, seal means carried by the lower end of the ram to seal it inside the ram cylinder, means for pumping oil from the reservoir to the ram cylinder under pressure, a tank nut mounted at the top of the tank cylinder and rigidly secured to it, a retainer ring carried by the tank nut, a pair of ram bearing rings carried by said tank nut and reacting against said retainer ring, an O-ring seal between said bearing rings and engaging the ram to prevent leakage of oil from the jack, the top of said ram cylinder extending in but being spaced from the inside of the tank nut and being free floating with respect to the tank nut and tank cylinder.
